UNITED STATES PATENT OFFICE.

HARRY LANDSIEDEL, OF NORWOOD, OHIO, ASSIGNOR TO THE DALTON ADDING MACHINE COMPANY, OF CINCINNATI, OHIO, A CORPORATION OF OHIO.

CALCULATING MACHINE.

Application filed March 31, 1924, Serial No. 703,100. Renewed August 31, 1925.

To all whom it may concern:

Be it known that I, HARRY LANDSIEDEL, a citizen of the United States, residing at Norwood, Hamilton County, Ohio, have invented a new and useful Calculating Machine, of which the following is a specification.

This invention relates to calculating machines.

10 An object of the invention is to provide a calculating machine with simplified mechanism operable in the performance of examples of addition or subtraction as desired, and actuators for actuating one part of said mechanism directly in the performance of examples of addition, and for actuating another part of said mechanism directly in the performance of examples of subtraction.

Another object of the invention is to provide a calculating machine equipped with mechanism of the character and operating in the manner stated and in which the two parts of the mechanisms controlled directly by said actuators are themselves operably connected so that that part of said mechanism which is operated by said actuators will operate the other part of said mechanism.

Another object of the invention is to equip an adding and listing machine of known construction and mode of operation with the mechanisms mentioned.

Other objects will appear from the following description, reference being made to the drawings in which

35 Fig. 1 is a side elevation of the present invention embodied in a Dalton adding machine.

Fig. 2 is an enlarged view showing the calculating pinions and actuating racks therefor in their normal or clear positions.

40 Fig. 3 is a view of the same devices in the positions they occupy when making a transfer from lower to higher denominational orders.

45 Fig. 4 is a view of the calculating pinions and actuating racks indicating the direction of operation in performing examples of subtraction.

50 Fig. 5 is a plan view showing the relationship of the parts shown in Fig. 4.

Fig. 6 is a view of the calculating pinions and actuating racks indicating the direction of operation in performing examples of addition.

Fig. 7 is a plan view showing the relationship and position of the parts shown in Fig. 6.

Fig. 8 is a rear elevation of the machine containing the invention.

Fig. 9 is a view showing a part of the devices for moving the pinions into and out of operative engagement with their operating racks.

The machine in which the present invention is shown comprises the usual numeral key levers 1, differential mechanism 2, the racks 3 controlled by the differential mechanism and associated with and limiting extent of movement of the type carriers 4, the shaft 5 upon which the type carriers and racks are pivotally supported, the laterally movable paper carriage 6 having a platen therein for feeding paper to be printed upon by type 7 mounted on the type carriers, hammers 8 for driving the type 7 to print on the paper in the paper carriage, adding pinions 9 operated by the racks 3 in adding and clearing operations, a total key 10, the subtotal key 11 and the link 12 controlled by the total key and subtotal key. The link 12 controls the parts permitting operation of the machine in clearing and subtotal operations in the usual manner. The type carriers and racks are actuated forwardly by springs 13 connected to the rearwardly extended arms 14 in connection with the type carriers and are returned to their starting positions by a bail rod 15 operated in the usual manner by connections from the main shaft 16.

The present invention is cooperatively associated with the above described familiar mechanism. Each type carrier arm 14 has a link 17 connecting it with a slide 18 guided by a grooved shaft 19. A rack plate 20 is mounted on each of the slides 18 by pin and slot connection 21. Each plate 20 is provided with two racks formed in different vertical planes, of which the rack 22 is at the upper end of the plate and the 100

rack 23 is at the lower end of the plate and is offset laterally toward the right hand side of the machine relative to the rack 22. The plate 20 is actuated upwardly by a spring 24.

An upper shaft 25 and a lower shaft 26 are supported by a pair of swinging arms 27, the lower ends of which are connected with the shaft 28. A series of pinions 29 are rotative on the shaft 25 by the racks 22, and a series of pinion 30 are rotative on the shaft 26 by the racks 23. The pinions 29 mesh with the pinions 30 and are in vertical alinement therewith so that when the pinions 29 are engaged with the racks 22 the pinions 30 are out of engagement with the racks 23 and vice versa (Figs. 5 and 7). Each of the pinions 29 is attached to a transfer trip disc 31 having a cam shoulder 32 for each series of ten teeth on the pinions. As shown each pinion 29 is provided with forty teeth, so that there are four cam shoulders 32 on each of the discs 31. Each of the pinions 30 is attached to a transfer trip disc 33 having a cam shoulder 34 for each series of ten teeth on the pinion. As shown, each pinion 30 is provided with forty teeth so that there are four cam shoulders 34 on each of the discs 33. A series of transfer latches 35 for the discs 31 are pivotally supported upon a rod 36 and have shouldered ends 37 upon which the cam shoulders 32 rest when the calculating device is clear and when the pinions 29 engage the racks 22 (Fig. 2). A series of transfer latches 38 for the discs 33 are pivotally supported upon a rod 39 and have shouldered ends 40 against the beveled under edges of which the beveled edges of the cam shoulders 34 rest when the calculating device is clear and when the pinions 30 engage the racks 23. But when the pinions 29 are in line with their racks 22 and their latches 35 the pinions 30 are out of line with their racks 23 and their latches 38, and vice versa. The latches 35 are connected with the corresponding latches 38 by links 41 and both series of latches 38 are actuated to latching position by springs 42 connected with the latches 38. Also, each two connected latches 35 and 38 are moved to unlatching position at the same time because of their link connection 41 (Fig. 3).

When the machine is clear and at rest pawls 43, pivotally supported upon a rod 44, extend over and engage the upper ends of the rack plates 20 and thereby hold said rack plates down in their lower positions. The pawls 43 have fingers 45 on their lower ends engaging extended portions of the latches 35 when said latches 35 are in latching position. The pawls 43 are thereby held in position to prevent upward transfer movement of the rack plates 20. When any one of the latches 35 is operated by its corresponding transfer trip disc 31, or when any one of the

latches 38 is operated by its corresponding disc 33, the extended portion of the latch 35 is raised above the finger 45 (Fig. 3) permitting the spring 46 of the corresponding latch pawl 43 to actuate the same from the position shown in Fig. 2 to the position shown in Fig. 3, thus permitting upward transfer movement of the corresponding rack plate 20. This is irrespective of whether the latches 35 and 38 were operated by the transfer trip disc 31 or by the transfer trip disc 33. After any transfer movement the released pawl or pawls 43 are restored to normal position by a bail 47 supported on the rod 44 and operated by a link 48 at the next operation of the main shaft 16 of the machine, as hereinafter described.

I will now describe the mechanism for shifting the pinions 29 and 30 to and from positions for operation by their respective racks 22 and 23. The normal position is that in which the pinions 29 are in position for operation by the racks 22 and in which the pinions 30 are out of line with their racks 23 (Figs. 6 and 7). When the parts are in such relationship the machine may be operated in ordinary addition. When it is desired to operate the machine in the performance of examples of subtraction it is necessary to shift the pinions to position so that the pinions 30 will be operated by the racks 23 so that the pinions 29 will be out of line with the racks 22. A pair of arms 49 engaging a grooved part 50 of the shaft 28 are rigid with a rod 51. An arm 52 (Figs. 1 and 8) also rigid with the rod 51 has a projection 53 engaging in a cam slot 54 in vertically sliding support 55 which is normally in its lower position thereby holding the shaft 28 in an adjustment in which the pinions 29 are in line with the racks 22, thus normally maintaining the machine in condition for operation in ordinary addition. When the sliding support 55 is raised the connections are operated to shift the shaft 28 to move the pinions 30 into line with the racks 23 and move the pinions 29 out of line with the racks 22. A normally raised subtraction key lever 56 (Fig. 1) is pivotally supported on a shaft 57. A link 58 is pivoted to an extension of the lever 56 above the shaft 57 and is moved forwardly when the key lever 56 is depressed. A part 59 is pivoted to the rear end of the link 58 and has pin and slot connection 60 with the support 55. A hook 61 is on the part 59. A pair of spaced rocking parts 62 are on a support 63 and support a cross connection 64 above which the hook 61 is extended when the key lever 56 is depressed. The link 48 connects one of the parts 62 with the bail 47 so that when the parts 62 are rocked the link 48 will be operated to depress the bail 47 and restore the transfer mechanism to normal position. A link 66 is pivotally con-

nected with one of the parts 62 and has pin in slot connection 67 with an arm 68 attached to another arm 69 upon a support 70. A link 71 connects the arm 69 with an arm 72 on the main shaft 16. Thus, when the key lever 56 is depressed to move the hook 61 over the cross connection 64 and the main shaft 16 is thereafter turned in a forward direction, the link 71 will operate the connections therefrom first to raise the cross connection 64 and thereby raise the hook 61 and the support 55, shifting the shaft 28 toward the left when viewed from the rear (Fig. 8) thereby moving the pinions 30 and their connected transfer trip discs 33 to co-operative relationship with the racks 23 and the latches 35 respectively; and also moving the pinions 29 and their connected transfer discs 31 out of co-operative relationship with the racks 22 and the latches 33 respectively. One edge of the support 55 has notches 73 with which a spring actuated latch detent 74 engages to hold said support 55 in its raised or lowered position. The latch detent 74 will hold the support 55 in its raised position so long as the key lever 56 remains depressed to hold the hook 61 above the cross connection 64. If the key levers 56 be raised the link 58 moves to the rear, thereby moving the hook 61 out of position for engagement by the cross connection 64 and moving a finger 75 in position for engagement by a cross connection 76 between the parts 62 on the next operation of the main shaft 16. Contact of the cross connection 76 with the finger 75 will push the support 55 to its lower position and, through the connections described, will move the pinions 29 and their connected transfer trip discs 31 to cooperative relationship with the racks 22 and latches 33 respectively; and will move the pinions 30 and their connected transfer trip discs 33 out of cooperative relationship with the racks 23 and the latches 35 respectively.

The mechanism for swinging the pinions 29 and 30 into and out of engagement with their racks 22 and 23 is somewhat similar to the mechanism disclosed for the performance of the same duties in the application of Walter Wm. Landsiedel, Serial No. 686,023, filed January 14, 1924. As shown (Figs. 1 and 9) a cam plate 77 is pivoted upon a support 78 and engages a roll 79 upon the adjacent arm 27. When the high point of the cam plate 77 engages the roll 79 it retains the pinions 29 and 30 in position for operation by the racks 22 and 23 as the case may be, depending upon the lateral positions of said pinions; and when the low part of the cam plate 77 is in line with the roll 79, the arms 27 swing to position to carry the pinions 29 and 30 out of position for operation by the racks 22 and 23. At the beginning of each forward turning movement of

the shaft 16, except in the case of lifting a total or result, the cam plate 77 is moved to permit disengagement of the pinions from the racks, and at the beginning of each return movement of the shaft 16 the cam plate 77 is operated to engage the pinions with the racks.

An oppositely shouldered pawl 80 is pivotally supported by the arm 68 and operated in one direction by a spring 81. A member 82 pivoted on the support 78 has an arm 83 pivoted to a plate 84 having pin in slot connection 85 with the cam plate 77. The pivotal connection between the arm 83 and the plate 84 comprises a pin on the arm 83 extending into a cam slot 84 in the plate 81. By reference to Fig. 1 it will be seen that at the beginning of the forward turning movement of the shaft 16 the shoulder on one side of the pawl 80 will engage a projection 86 on the member 82 and operate the connected parts to move the high point of the cam plate 77 from the roll 79. At the beginning of the back or return turning movement of the shaft 16 the shoulder on the opposite side of the pawl 80 engages a projection 87 on the member 82 and moves the high point of the cam against the roll 79 thereby engaging the pinions 29 with the racks 22, or the pinions 30 with the racks 23 as the case may be.

When the machine is to be cleared or any total or remainder contained in the pinions 29 or 30 is to be printed, it is necessary that the pinions remain in mesh with their respective racks 22 or 23 on the forward stroke. The link 12 that is pushed to the rear by operation of either the total key 10 or subtotal key 11 has connections for disabling the devices that operate the cam 77 at the beginning of the forward turning movement of the shaft 16. Said link 12 has an arm 88 connected by a link 89 with an arm on one end of a transverse shaft 90 like the arm 91 that is shown on the near end of said shaft (Fig. 1). A link 92 connects the upper end of the arm 91 with the upper arm of a bell crank lever 93 pivoted on a support 94. The other arm of the bell crank lever 93 extends over a projection 95 on the plate 84 which has a slot 96 permitting sliding movement of said plate on the support 78. When the link 12 is moved toward the rear the horizontal arm of the bell crank lever 93 is moved downwardly and, by contact with the projection 95, pushes the plate 84 downwardly. The pin in slot connection between the member 82 and the plate 84 turns the member 82 to a position in which it will not engage the pin 86 during the forward stroke. This leaves the pinions 29 or 30 in mesh with their racks 22 or 23 as the case may be. The key 10 holds the link 12 in its rearward position during the return stroke so that

the shouldered pawl 80 will engage the projection 87 at the beginning of the return stroke and disengage the pinions 29 and 30 from the racks 22 and 23 as the case may be, leaving the calculating mechanism clear. But, when the key 11 is operated for the purpose of taking a subtotal, the link 12 does not remain rearward but moves forwardly at the beginning of the return stroke, thus permitting the plate 84 to be raised by a spring 97. When the plate 84 is in its raised position the pawl 80 will not engage the projection 87 during the return stroke, leaving the pinions 29 and 30 in mesh with their racks 22 and 23.

The invention is capable of wide variation within equivalent limits and I contemplate such variation as may be desirable or useful in the particular adaptation of the invention shown, or in its adaptation to other machines.

I do not restrict myself in any unessential particulars, but what I claim and desire to secure by Letters Patent is:—

25 1. A calculating machine comprising a series of actuators, two series of racks operated by said series of actuators, a series of pinions for operation by each series of racks, a series of transfer latches for each series 30 of pinions, and connections for operating one series of transfer latches by the other.

35 2. A calculating machine comprising a series of actuators, two series of connected racks operated by said actuators, a series of pinions for operation by each series of racks, devices for preventing transfer operation of said racks, and means operated by either series of pinions for releasing said devices to permit transfer operation of said 40 racks.

45 3. A calculating machine comprising a series of rack plates, two series of racks in connection with said rack plates, mechanism for operating said rack plates, a series of pinions for operation by each series of rack plates, a series of transfer devices for each series of pinions, and means operating the transfer devices of one series by the transfer devices of the other series.

50 4. A calculating machine comprising two series of racks, two series of intermeshing pinions for operation by said series of racks respectively, means for shifting said pinions to mesh either series of pinions with the corresponding series of racks, and transfer mechanism controlled by said pinions for controlling transfer operation of said racks.

55 5. A calculating machine comprising two series of connected unaligned racks, two series of pinions for operation by said two series of racks respectively, an element holding each pair of connected racks from transfer movement, and a device operated by each series of pinions for causing said elements to release said racks for transfer movement.

6. A calculating machine comprising two series of connected unaligned racks, two series of intermeshing pinions for operation by said two series of racks respectively, mechanism for shifting said two series of pinions to positions in which either series of the pinions will be operated by the corresponding series of racks, and mechanism controlled by each series of pinions controlling transfer operations of said racks.

7. A calculating machine comprising two series of connected unaligned racks, two series of intermeshing pinions for operation by said two series of racks respectively, mechanism for shifting said two series of pinions to positions in which either series of the pinions will be operated by the corresponding series of racks, an element holding each pair of connected racks from transfer movement, and mechanism controlled by each series of pinions for causing said elements to release said racks for transfer movement.

8. A calculating machine comprising a series of racks, an additional series of racks out of alignment with said first series of racks, two series of intermeshing pinions for operation by said two series of racks respectively, means for moving said pinions to mesh either series of pinions with the corresponding series of racks, and mechanism for operating said racks.

9. A calculating machine comprising a series of racks, an additional series of racks out of alignment with said first series of racks, (two series of intermeshing pinions for operation by said two series of racks respectively, means for moving said pinions to mesh either series of pinions with the corresponding series of racks, mechanism for operating said racks, and transfer mechanism controlled by each series of pinions for controlling transfer operation of said racks.

10. A calculating machine comprising a series of racks, an additional series of racks out of alignment with said first series of racks, two series of intermeshing pinions for operation by said two series of racks respectively, means for moving said pinions to mesh either series of pinions with the corresponding series of racks, mechanism for operating said racks, transfer mechanism controlled by each series of pinions for controlling transfer operation of said racks, and means for restoring said transfer mechanism to non-transferring position.

11. A calculating machine comprising differential mechanism, a series of type carriers controlled by said differential mechanism, two series of racks operated by said type carriers, a series of pinions for each series of racks, means for meshing either series of pinions with the corresponding se- 130

ries of racks, and means controlling transfer operation of said racks.

12. In a calculating machine, the combination with a series of differentially operable type carriers, of two series of racks operated by said type carriers, a series of pinions for operation by each series of racks, and a series of elements controlled by both series of pinions controlling transfer operation of said racks.

13. In a calculating machine, the combination with a series of differentially operable type carriers, of a series of actuators operated by said type carriers, two series of racks

15 operated by said actuators, two series of intermeshing pinions for operation by said two series of racks respectively, mechanism for meshing either series of pinions with the corresponding series of racks, and transfer mechanism controlled by said pinions controlling transfer operation of said racks.

14. In a calculating machine, the combination with a series of differentially operable type carriers and adding mechanism 25 operated by said type carriers, of a set of actuators operated by said type carriers, a series of racks operated by said actuators, a series of calculating pinions operated by said racks, and transfer mechanism controlled by said calculating pinions controlling transfer operation of said racks.

15. In a calculating machine, the combination with differentially operable type carriers, of a series of slides operated by said type carriers, a pair of racks supported by said slides, two series of intermeshing pinions for operation by the racks of said pairs of racks respectively, and mechanism controlled by said pinions controlling transfer operation of said racks.

16. In a calculating machine, the combination with differentially operable type carriers, of a series of slides operated by said type carriers, a pair of racks supported by said slides, two series of intermeshing pinions for operation by the racks of said pairs of racks respectively, mechanism controlled by said pinions controlling transfer operation of said racks, a swinging frame supporting said two series of pinions, and mechanism controlling said frame to hold said pinions in proper relationship to said racks.

17. A calculating machine comprising a series of slides, two series of racks supported by said slides in a relationship in which the racks of each series are out of alinement with the racks of the other series, a series of intermeshing pinions for operation by each series of racks, mechanism for shifting said pinions from one position to another to mesh either series of pinions with the corresponding series of racks, and means controlling transfer operation of said racks.

18. A calculating machine comprising a series of slides, two series of racks supported by said slides in a relationship in which the racks of each series are out of alinement with the racks of the other series, 70 a series of intermeshing pinions for operation by each series of racks, mechanism for shifting said pinions from one position to another to mesh either series of pinions with the corresponding series of racks, 75 means controlling transfer operation of said racks, and mechanism for clearing said pinions.

19. A calculating machine comprising a series of slides, two series of racks supported 80 by said slides in a relationship in which the racks of each series are out of alinement with the racks of the other series, two series of intermeshing pinions for operation by said series of racks respectively, a series of 85 transfer latches for each series of pinions, a series of transfer trip elements for each series of pinions for tripping the corresponding series of latches, and means controlled by said latches controlling transfer 90 operation of said racks.

20. A calculating machine comprising a series of slides, two series of racks supported by said slides in a relationship in which the racks of each series are out of alinement 95 with the racks of the other series, two series of intermeshing pinions for operation by said series of racks respectively, a series of transfer latches for each series of pinions, 100 a series of transfer trip elements for each series of pinions for tripping the corresponding series of latches, means controlled by said latches controlling transfer operation of said racks, and means for moving said series of pinions to place either 105 series of pinions in cooperative relationship with the corresponding series of racks and latches and the other series out of cooperative relationship with its corresponding 110 series of racks and latches.

21. A calculating machine comprising two series of connected racks arranged in a relationship in which the racks of each series are out of alinement with the racks of the other series, mechanism for operating said racks, two series of intermeshing pinions for operation by said series of racks respectively, a series of transfer latches for each series of pinions, a series of tripping elements for each series of pinions for tripping the corresponding transfer latches, and means for moving said series of pinions and said tripping elements to place either series of pinions and tripping elements in cooperative relationship with the corresponding series of racks and transfer latches.

22. A calculating machine comprising two series of connected racks arranged in a relationship in which the racks of each series are out of alinement with the racks

- 6 of the other series, mechanism for operating said racks, two series of intermeshing pinions for operation by said series of racks respectively, a series of transfer latches for each series of pinions, a series of tripping elements for each series of pinions for tripping the corresponding transfer latches, means for moving said series of pinions and said tripping elements to place either series of pinions and tripping elements in cooperative relationship with the corresponding series of racks and transfer latches, and a device controlled by each latch of one series of latches controlling transfer operation of the corresponding rack and the connected rack. 65

26. A calculating machine comprising a shaft, a series of type carriers pivoted upon said shaft, a series of racks pivoted upon said shaft, adding mechanism operated by said racks, a series of supports pivotally connected with said type carriers, racks carried by said supports, and calculating mechanism operated by said last named racks. 26
- 20 25 30 35 40 45 50 55 60 65 70 75 80 85 90 95 100 105 110 115 120 125
27. A calculating machine comprising a shaft, a series of type carriers pivoted upon said shaft, a series of racks pivoted upon said shaft, adding mechanism operated by said racks, a series of supports pivotally connected with said type carriers, racks carried by said supports, calculating mechanism operated by said last named racks, and means controlling transfer operation of said last named racks. 27
- 20 25 30 35 40 45 50 55 60 65 70 75 80 85 90 95 100 105 110 115 120 125
28. A calculating machine comprising a series of pivoted arms, a series of pivoted racks limiting extent of movement of said arms in one direction, adding mechanism operated by said racks, a set of calculating pinions, and mechanism operated by said arms for operating said calculating pinions. 28
- 20 25 30 35 40 45 50 55 60 65 70 75 80 85 90 95 100 105 110 115 120 125
29. A calculating machine comprising a series of pivoted arms, a series of pivoted racks limiting extent of movement of said arms in one direction, adding mechanism operated by said racks, a set of calculating pinions, mechanism operated by said arms for operating said calculating pinions, and means controlling transfer operation of said mechanism. 29
- 20 25 30 35 40 45 50 55 60 65 70 75 80 85 90 95 100 105 110 115 120 125
30. A calculating machine comprising a shaft, racks pivoted on said shaft, adding mechanism operated by said racks, differential mechanism limiting extent of movement of said racks, arms pivoted on said shaft, a set of calculating pinions, and mechanism controlled by said arms for operating said calculating pinions. 30
- 20 25 30 35 40 45 50 55 60 65 70 75 80 85 90 95 100 105 110 115 120 125
31. A calculating machine comprising a shaft, racks pivoted on said shaft, adding mechanism operated by said racks, differential mechanism limiting extent of movement of said racks, arms pivoted on said shaft, a set of calculating pinions, mechanism controlled by said arms for operating said calculating pinions, and recording mechanism cooperative with said racks, said adding mechanism and said calculating pinions. 31
- 20 25 30 35 40 45 50 55 60 65 70 75 80 85 90 95 100 105 110 115 120 125
32. A machine of the character described comprising a series of pivoted arms, a series of supports pivotally supported by said arms, calculating mechanism, and means carried by said supports for operating said calculating mechanism in adding and transfer operations. 32
- 20 25 30 35 40 45 50 55 60 65 70 75 80 85 90 95 100 105 110 115 120 125
33. A machine of the character described comprising a shaft, a series of pivoted arms, a series of supports pivotally supported by

6 said arms, calculating mechanism, and means carried by said supports for operating said calculating mechanism in adding and transfer operations, in combination with a series of racks pivoted on said shaft for limiting extent of movement of said arms, differential mechanism controlling said racks, and adding mechanism operated by said racks.

10 34. A machine of the character described comprising a shaft, a series of pivoted arms, a series of supports pivotally supported by said arms, calculating mechanism, and means carried by said supports for operating said calculating mechanism in adding and transfer operations, in combination with a series of racks pivoted on said shaft for limiting extent of movement of said arms, differential mechanism controlling said racks, adding mechanism operated by said racks, and 20 recording mechanism operative to record numbers from said calculating mechanism and from said adding mechanism.

35. A calculating machine comprising two

series of racks, a single series of supports for supporting and operating said two series of racks, and two series of calculating pinions operated by said two series of racks respectively.

36. A calculating machine comprising two series of racks, a single series of supports for supporting and operating said two series of racks; two series of calculating pinions operated by said two series of racks respectively, and recording mechanism cooperative with said calculating pinions.

37. A machine of the character described comprising differential mechanism, a series of racks controlled by said differential mechanism, adding pinions operative by said racks, two additional series of racks controlled as to extent of movement by said first series of racks, and calculating mechanisms operated by said two additional series of racks.

HARRY LANDSIEDEL.
